(Model.)

R. S. WEROTTE.
PUMP.

No. 248,538.

Patented Oct. 18, 1881.

UNITED STATES PATENT OFFICE.

RUDOLF SCHMITZ WEROTTE, OF WEST BROMPTON, COUNTY OF MIDDLESEX,
ENGLAND.

PUMP.

SPECIFICATION forming part of Letters Patent No. 248,538, dated October 18, 1881.

Application filed May 10, 1881. (Model.)

To all whom it may concern:

Be it known that I, RUDOLF SCHMITZ WEROTTE, a subject of the Queen of Great Britain and Ireland, residing at West Brompton, in the county of Middlesex, Kingdom of Great Britain and Ireland, have invented new and useful Improvements in Pumps, (partly applicable for other purposes,) of which the following is a specification.

10 In a pump according to this invention valves are dispensed with. The pump has several chambers or barrels—say conveniently six—which are arranged with their axes radial to a center, around which the series revolves. These 15 pump chambers or barrels are formed in a metal disk or pump-body, which I will call the “pump-disk.” It is driven by a pulley or by other suitable means, and thus caused to rotate about the center, which is a fixed coned center, 20 in which are formed the suction and delivery chambers. The pistons of the pumps are each connected by a pin or bolt to two disks, rings, or straps, one on each side of the pump-disk. These disks, which I will call the “eccentric-disks,” 25 rotate about a common axis, which is eccentric to the pump-disk axis. These eccentric-disks are each connected to the pump-disk, so as to revolve with it, by means of external gearing, or by what I call “connecting-disks,” 30 and these connecting-disks may be situated at any convenient point. In the arrangement illustrated they are arranged with their axes between two pump-barrels; but they may be arranged with their axes in a plane common 35 with the axis of a pump-barrel, this arrangement reducing the number of working parts.

I may apply my improved pump to the construction of “cataract-governors” of the kind described in the specification of Letters Patent 40 granted to me the 6th day of April, 1880, No. 226,257.

Figure 1 of the drawings is a plan, partly in section, of my improved pump, wherein the connecting-disks are placed with their axes 45 between two pump-barrels; and Fig. 2 shows two longitudinal vertical half-sections of the same, one taken in the line A.B of Fig. 1, through the center of a pump-barrel, and the other in the line C.D of Fig. 1, through the center of 50 a pair of connecting-disks.

a a are the pump chambers or barrels, formed in the metal disk or body *b*.

c is a pulley, secured on the extension *b'* of the pump-disk *b*, for driving the same.

d is a fixed coned center, around which the 55 pump-disk rotates, and in which are formed the suction-chamber *e* and the delivery-chamber *f*.

The pistons of the pumps are each connected by means of a pin or bolt, *h*, to two rods or 60 arms, *g*, pivoted at *g'*, respectively, to two disks, rings, or straps, *i* and *j*, which rotate on similar fixed portions *i' j'* of the apparatus, having their centers eccentric to the center of the pump-disk. The eccentric disks *i j* are connected to the pump-disk by means of connecting-disks *k l*, fitting into recesses formed in the pump-disk, so as to rotate therein, and having pins or bolts *h'* connected to the eccentric-disks *i j*, and passing through the connecting-disks 70 eccentrically to their centers, according to the length of stroke of the pistons.

d' are pillars or supports for carrying the upper fixed plate, forming the eccentric portion *i'*.

As the pump-disk *b* becomes worn it may be 75 screwed up to the coned center *d* by means of the screws and nuts *d''*, acting upon the upper plate, *i'*.

Instead of driving the pump-disk by a pulley, *c*, it and the eccentric-disks *i j* may be 80 driven by a pinion gearing into teeth formed on their outer extremities, as shown in dotted lines. The apparatus may be placed in a tank or other receptacle containing water or other liquid.

It will be understood that as the pump-disk is rotated the pistons are caused to reciprocate, their movement being outward when passing the suction-chamber side of the center *d*, so as then to draw liquid or fluid into them 90 through *e'*, which liquid or fluid, as it passes round the other side of the center *d*, is, by the inward movement of the pistons, forced into the outlet-chamber *f* through a hole or holes, such as *e'*.

x is an interposed layer of anti-frictional material.

My pump may be modified by dispensing with one of the eccentric-disks *i* or *j*.

My improved valveless pump is applicable 100

to various purposes—such as for drawing and forcing liquids and fluids, measuring, air-compressing, hydraulic governors, &c.

What I claim is—

- 5 1. In a pump, the combination of a conical center or axis containing suction and delivery chambers with a revolving disk or pump-body containing any number of radiating pump chambers or barrels fitted with pistons, substantially as described.
- 10 2. In a pump, the combination of a hollow conical center or axis containing suction and delivery chambers, a revolving disk or pump body containing any number of radiating pump chambers or barrels containing pistons, and one or more revolving disks, rings, or straps, running upon fixed eccentrics, and connected to said pistons by pins and links in any suitable manner, substantially as described.
- 15 3. In a pump, the combination, with a revolving disk or pump body containing radiating pump chambers or barrels and pistons, and adapted to rotate on a hollow conical center or axis, and one or more revolving disks, rings,

or straps running upon fixed eccentrics and connected to said pistons, of connecting-disks to interlock the pump disk or body with the eccentric disks, rings, or straps in such a way that all may revolve together, substantially as described.

4. In a pump, the combination, with a hollow conical center or axis containing suction and delivery chambers, and on which revolves a disk or pump body containing radiating pump chambers or barrels, of pinions or pulleys fixed upon an axial extension of the pump disk or body, or gearing into teeth on the circumference of the pump-body, and eccentric disks, rings, or straps, designed to impart rotary motion to the whole system, substantially as described.

R. SCHMITZ WEROTTE.
